UNITED STATES PATENT OFFICE.

ALFRED B. WILLOUGHBY, OF PHILADELPHIA, PENNSYLVANIA.

IMPACT PULVERIZER.

Application filed January 31, 1925. Serial No. 5,927.

My invention relates to impact pulverizers of the type or class in which two aligned and opposing streams of material to be pulverized are discharged at a high velocity against each other by jets of superheated steam to reduce the material in said streams to a fine powdered condition by the impact of the pieces against each other.

The type of apparatus to which my invention relates is exemplified in U. S. Letters Patent No. 1,246,514, granted to me November 13, 1917 and the present invention involves certain improvements in such apparatus.

15 The object of the present invention is to increase the capacity or rate at which material reduced to a powdered condition may be removed from the chamber in which it is reduced to its powdered condition; to remove 20 the material substantially as fast as it is formed in the pulverizing or impact chamber, and to so construct said chamber that the finely powdered material may not collect and accumulate in the said chamber or be 25 come mixed and carried along with the larger particles which, in the normal operation of the device, are resubjected to the action of the pulverizer.

Further objects of my invention are to 30 provide an impact or pulverizing chamber in which all the material, after impact, is forced to pass transversely through a fluid current to completely separate the pulverized material from the particles which are not 35 pulverized and which require a retreatment; to provide a structure whereby all of the fragments which require further treatment are immediately discharged or conducted out 40 of the pulverizing chamber and may not accumulate therein.

A further object of my invention is to cause the heavier particles to travel over and to keep clear of powdered material, any surface inside of said casing upon which said 45 powdered material might tend to accumulate.

A further object of my invention is to cause all the unpulverized material after impact to move toward and discharge through an opening in the bottom of the pulverizer 50 chamber through which air is being drawn into the pulverizing chamber.

A further object of my invention is to provide the pulverizing box or chamber with a large number of exhaust pipes or conduits, 55 each provided with an ejector so that when

material is being rapidly pulverized it may be removed from the pulverizing chamber as fast as it is formed without increasing the rate at which any one ejector may be operating. It may here be explained that ejectors employed in pulverizing apparatus of the type referred to herein are more or less uncertain in their operation when it is attempted to operate them under varying conditions; that is to say, when the steam at 60 just the right velocity and quantity is forced into and through the Venturi tube, the ejector operates very satisfactorily. The amount and speed of the projecting fluid which will operate most efficiently with a particular 65 Venturi tube are determined more or less by experimentation, and after a particular ejector has been so adjusted to operate properly the ejector is efficient. But any attempt to make the action of an ejector of this type 70 more rapid, as by increasing the amount of steam delivered thereto, may result in a substantial decrease in the efficiency of the apparatus. It is, therefore, highly desirable 75 to operate the ejectors under constant conditions; that is to say, with that pressure and a volume of steam which operates most efficiently with the Venturi tube of the particular ejector.

The speed at which different materials 80 may be pulverized in an impact pulverizer depends, of course, upon materials. Some materials are reduced to a powder much more quickly than others. Therefore, the speed at which the material may be taken 85 from the pulverizer chamber varies with different materials. With a material which is easily reduced, the powdered material may be formed in the pulverizing chamber faster than it can be carried away by a single 90 ejector, and to remove the material as fast as it is formed, being one of the objects of the present invention, I accomplish the removal by providing the side and top walls of the 95 pulverizing chamber each with an independent ejector apparatus so that, for instance, in treating a readily pulverized material, two or three or even four independent ejectors may be simultaneously operated, each operating under the conditions best suited or 100 peculiar to itself. When one, two or more ejectors are operating simultaneously, each ejector will act as it would if it were operating alone. In treating materials which are 105 reduced with difficulty, and therefore rel- 110

atively slowly, one ejector apparatus might suffice to remove the pulverized material as fast as it is formed.

Other objects of my invention will appear in the specification and claims below.

In the drawings forming a part of this specification and in which the same reference characters are used throughout the various views to designate the same parts,

10 Fig. 1 is a front elevational view, partly in section of a pulverizer embodying my invention.

Fig. 2 is a side elevational view of the same, partly in section.

15 Fig. 3 is a plan view of the same, parts being broken away to show the interior of the pulverizer chamber; and

20 Fig. 4 is a more or less diagrammatic view of an arrangement whereby varying amounts of pulverized material may be removed from the pulverizing chamber.

The apparatus comprises a pair of hoppers 1—1, the lower ends of which are arranged to discharge into chambers 2—2 provided in the casing 3, said chambers each surrounding a steam nozzle 4 rigidly secured by screwthreads 5 to the rear wall of the chamber 2. The passage 6 through the steam nozzle 4 is in alinement with an opening 7 through the casing, communicating with the end of a steam pipe 8 through which steam superheated to high temperatures and at a high pressure, is conducted to the nozzles. Into the outer end of each nozzle 4 is secured a tube or nipple 9 of very hard steel, the nipple being preferably secured to the nozzle by screwthreads 10. The jet openings 11 through the nipples 9 are of very small diameter and the superheated steam from the pipe 8 will issue therefrom at very high pressure and velocity. The side of each chamber 2 opposite that to which the steam pipes 8 are attached is preferably provided with a large opening 12 into which is rigidly secured in any suitable manner a bushing 13 having a concentric circular hole 14 therethrough into which are tightly fitted wearing tubes 15 of hard steel, each having an axial tapering passage 16 therethrough in axial alinement with the axis of the passage 11 through the steam nipples 9.

The adjacent ends of the wearing tube 15 are provided with a flange 17 fitting against and substantially covering the inner faces of the bushings 13. The wearing tubes 15 are preferably secured to the bushings by set screws 18 so that when the wearing tubes become worn they may be readily replaced.

60 The inner ends of the bushings 13 and wearing tubes 15 are enclosed within a suitable casing or housing 19 forming the impact or pulverizing chamber 20. The side walls 21, 22 of the pulverizing chamber are preferably vertical and are parallel but they

are preferably spaced further apart from each other at the rear of the apparatus (see Fig. 3) than at the front to provide an enlarged portion 20' in which the separation of the powder from the unpowdered material may be more readily effected.

70 The top wall of the pulverizer chamber 20 comprises two portions, namely, the horizontal wall portion 23 forming the top of the separating portion 20' of the chamber, 75 and the inclined portion 24 extending forwardly and downwardly from the front edge of the wall 23 to a position in front of and substantially at the level of the axis of the nozzles 4. The rear wall 25 of the pulverizing chamber is preferably vertical.

75 The bottom wall of the pulverizer chamber 20 preferably comprises two downwardly converging steeply inclined walls 26 and 27, the lower ends of which are spaced from each other to provide a relatively narrow and long passage 28 extending the full width of said chamber.

80 The pulverizer chamber is preferably constructed in two parts, an upper part or portion and a lower part or portion respectively provided with flanges 29 and 30 secured together with bolts 31.

85 The top horizontal wall 23, the rear vertical wall 25 and the upper portion of the side walls 21 and 22 are each provided respectively with a large opening 32, each communicating with a relatively large conveyor pipe or tube 33 having a Venturi tube 34 therein.

90 The Venturi tubes 34 are preferably removable so that they may be readily replaced when worn, and cooperating with each Venturi tube is a nozzle 35 at the end of a steam pipe 36 arranged axially of the tube 34 in which it may be and arranged to discharge a jet of steam at high temperature and pressure into and through said Venturi tube to produce a current of air and steam through the tube 33 to draw the powdered material out of the pulverizer chamber and to convey it to a suitable settling chamber (not shown).

95 Each pipe 36 is preferably located axially of the conveyor tube 33 in which it is and serves the double purpose of conveying steam to the Venturi tubes and of reheating the conveyor fluid to prevent the formation of moisture therein between the pulverizer chamber and the ejector. The steam must be kept dry in order to convey the powder floating therein and to deliver it into the settling chambers in a dry condition.

100 Near the point where the conveyor tubes 33 join to the pulverizer chamber, each steam pipe is connected to a branch pipe 37 extending radially through the tube 33 and provided with a hand controlled valve 38. These pipes 37 communicate with a suitable source of steam supply and the valves 105 38

make it possible for the operator to use as many conveyor tubes as may be required to carry off the material as fast as it is formed in the pulverizing chamber and to properly 5 adjust the amount of steam delivered to the Venturi tube by each conveyor so that each Venturi tube may be supplied with just the right amount of steam to operate efficiently independently of any other conveyor tube.

Below the chamber 2 in the casing 3 and forming the lower wall of said chamber 2 is a closure or gate 39 preferably pivoted on a bolt 40 so that the closure 39 may be swung 15 to one side when the handle 41 thereof is grasped and turned about the pivot 40 to give access to the chamber 2 whenever necessary.

Above the hopper 1, 1 is a main hopper 20 42 having its lower end bifurcated to form chutes 43, 43, terminating respectively over the hoppers 1, 1. The lower end of each chute 43 is preferably provided with a gate 44 pivoted on a stud 45 provided with a handle 46 so that the discharge of material from the main hopper 42 to either hopper 1 may be interrupted when desired.

Beneath the opening 28 at the bottom of the pulverizer chamber 20 is a chute or hopper 47 into which the particles of material being treated and which have not been reduced to a powder will fall by gravity. In the operation of this type of pulverizer, the chute 47 delivers material passing therethrough to a suitable conveyor mechanism by means of which the material which has not been reduced to the requisite fineness is carried back to the top of the apparatus and discharged again into the hopper for retreatment.

I preferably provide the chute 47 with branches 48 and 49 extending upwardly and having their upper ends respectively under the gates or closures 39 so that when either of said closures are opened for any reason, any material which may be in the chamber 2 may fall directly into a branch chute 48 or 49 and be carried by the main chute to the conveyor system.

The operation of my device is as follows: Material to be pulverized is introduced in the pulverizer from the hopper 42 through the branch chutes 43 into the hoppers 41 of the machine and the material to be treated substantially fills the hoppers 1 and the chambers 2 surrounding the steam nozzle 4. Superheated steam at high temperature and pressure is admitted through the steam pipes 8 to the steam nozzles 4 and the jets of steam drive through the tapered passage 16 in the wearing tubes 15 impelling forward with it at high speed the material to be pulverized which may be in the chambers 2, 2 and tapered passages 16, 16. Two streams of solid material thus are impelled at high

velocity against each other; it being now plain that the axes of the passages 6 through the nozzles 4 must be in alinement and the tapered passages 16 being also in alinement with each other. The force of the impact 70 of the particles or pieces of solid matter against each other pulverizes them and the dust and powder together with the particles which have not been reduced to powdered form, fly in all directions radially from the 75 point of impact which is substantially midway between the nozzles 4.

The powdered material is suspended in and floats in the air and steam as an im-palpable powder and the whole pulverizing 80 chamber 20 is immediately filled with this powder. The conveyor system having been started at the same time by opening one or more of the valves 38, the steam from the 85 end of the nozzle 35 of the conveyor driving through the Venturi tube 34, creates a draft or suction in the conveyor pipes 33 and draws the fluid (steam and air) up into the conveyor tube or tubes from the pulverizing chamber 20 and draws it through the 90 Venturi tube and on to suitable settling chambers.

It is to be noted that the inside of the pulverizer chambers contains no level or approximately level shoulders or surfaces. The 95 rear wall 25 is vertical. The front wall 24 is inclined downwardly. The bottom walls 26 and 27 slant downwardly sharply and no material of substantial weight can settle and remain thereon. However, the fragments or 100 particles of solid material which have not been reduced to powdered form are violently thrown and scattered over the entire interior surface of the pulverizing chamber 20 and being too heavy to be carried by the draft 105 of air provided in the conveyor 33 fall onto the sharply inclined walls 26 and 27 and slide down over the inner surfaces of the 110 walls dislodging any powder that might stick thereto and out through the opening 28 into the chute 4. But the movement of the heavier particles in the impact or pulverizing chamber is, generally speaking, transverse to and eventually against the direction 115 of the current of air or steam in the pulverizing chamber and drawn into the conveyor tubes; that is to say, the direction of the gaseous fluid in the pulverizing chamber is from the nozzles upwardly toward the conveyor tubes and from the opening or passage 28 upwardly to the conveyor tubes, while the direction of a great many of the heavier particles is either across the pulverizer chamber against the vertical rear wall 25 or downwardly against the inwardly 120 inclined walls 26 and 27 and eventually all the heavier particles will fall down through the opening or passage 28. In so falling their movement is against the movement of the gaseous fluid in the pulverizing chamber 125 130

4

ber. This movement of the heavier particles transverse to or against the direction of the fluid current frees them of the fine particles which are readily taken away through the 5 conveyor tubes, and as these heavier particles strike against the inner walls of the conveyor chamber or slide down over the inclined walls 26 and 27 they loosen and free any light particles which might adhere to the walls and, 10 being loosened, these light particles are carried upwardly by the current of steam and air and out of the chamber by the conveyor tubes.

If the nature of the material being treated 15 is such that it is rapidly reduced to a powdered condition, and, for instance, two conveyors which may be operating are not removing the powdered material from the chamber 20 as fast as it is formed, or as fast 20 as it may be desired to remove it, one or more other conveyors may be put into operation to remove the pulverized material without disturbing the adjustment or operation or interfering with the efficient operation 25 of the two conveyors which were already operating.

When, on the other hand, the nature of the material is such that it is slowly reduced to a powdered condition, the quantity of pulverized material produced may be so small 30 that it may be removed from the pulverizing chamber by operating a single conveyor.

From the above it will be seen that by 35 reason of the construction of the pulverizing or impact chamber and the action and movements of the incompletely treated and insufficiently reduced particles and the direction of the fluid current through the chamber all cooperating together, the interior of the pulverizing or impact chamber is kept clean of 40 any accumulation of completely reduced powdered material. There are no surfaces in the chamber on which the powder may lodge and remain and the powdered material is 45 kept suspended in the fluid traveling out of the pulverizing chamber and is carried along with the fluid through the tubular conveyors to suitable settling chambers.

Having thus described my invention, what 50 I claim and desire to protect by Letters Patent is:

1. In an impact pulverizer in which two aligned and opposed streams of material to be pulverized are discharged against each other impelled by jets of superheated steam under high temperature, pressure and velocity whereby the impact of the pieces against each other reduce them to a powder, the combination of a casing, forming an impact chamber and enclosing said jets and having an opening through the bottom thereof, below and offset horizontally from the vertical passing through the axes of said jets, a bottom wall of said casing being inclined sharply downwardly under both of

said jets, disposed in a plane parallel to the axes of said jets and terminating in said opening whereby unpulverized material striking against said inclined wall slides downwardly on said wall to said opening, and an 70 ejector communicating with the interior of said casing to remove the powdered material floating therein and to separate said powdered material from the heavier particles.

2. In an impact pulverizer in which two aligned and opposed streams of material to be pulverized are discharged against each other impelled by jets of superheated steam under high temperature, pressure and velocity whereby the impact of the pieces against each other reduce them to a powder, the combination of a casing, forming an impact chamber and enclosing said jets and having an opening through the bottom thereof offset horizontally from the vertical passing 75 through the axes of said jets, a bottom wall of said casing being inclined sharply downwardly under both of said jets and terminating in said opening whereby unpulverized material striking against said inclined wall 80 slides downwardly on said wall to said opening, and an ejector communicating with the interior of said casing to remove the powdered material floating therein and to separate said powdered material from the heavier particles, said heavier particles falling by 85 gravity out of said casing through said opening.

3. The combination with an impact pulverizer comprising a pair of aligned nozzles spaced apart and arranged to discharge toward each other streams of small pieces of solid matter impelled by superheated steam at high temperature, pressure and velocity whereby said pieces are pulverized by their impact against each other, of a casing forming an impact chamber and enclosing said nozzles, a bottom wall of said casing being inclined sharply downwardly, extending under both of said nozzles and terminating in 100 an opening below said jets and substantially offset from the vertical passing through the axes of said jets whereby any material from said nozzles not reduced to powder and striking said bottom wall will slide downwardly over the surface of said wall to said opening and an exhaust tube communicating with the interior of said casing at the upper portion thereof, and means to create a current of gaseous conveying fluid from said impact chamber through said exhaust tube to remove the pulverized material floating in said chamber and to separate said pulverized material from the heavier particles.

4. The combination with an impact pulverizer comprising a pair of aligned nozzles spaced apart and arranged to discharge toward each other streams of small pieces of solid matter impelled by superheated steam at high temperature, pressure and velocity 105 110 115 120 125 130

whereby said pieces are pulverized by their impact against each other, of a casing forming an impact chamber and enclosing said nozzles, a bottom wall of said casing being inclined sharply downwardly and extending directly under both of said nozzles and terminating in an opening offset laterally from the vertical passing through the axes of said jets whereby any material from said nozzles not reduced to powder and striking said bottom wall will slide downwardly over the surface of said wall to said opening and an exhaust tube communicating with the interior of said casing at the upper portion thereof, and means to create and to vary the velocity of a conveying gaseous fluid through said casing, comprising a plurality of Venturi tube fluid conveyors communicating with said casing and means to operate any and all of them separately or simultaneously.

5 10 15 20 25 30 35

6. The combination with an impact pulverizer comprising a pair of aligned nozzles spaced apart and arranged to discharge toward each other streams of small pieces of solid matter impelled by superheated steam at high temperature, pressure and velocity whereby said pieces are pulverized by their impact against each other, of a casing forming an impact chamber and enclosing said nozzles, a bottom wall of said casing being inclined sharply downwardly and positioned directly under both of said nozzles and terminating in an opening on one side of the vertical passing through the axes of said nozzles extending the full width of said casing whereby any material from said nozzles, not reduced to powder, and striking said bottom wall will slide downwardly on said wall out of said opening and will prevent any accumulation of powdered material on said wall, and means communicating with the upper portion of said casing to create a current of dry gas through said casing upwardly out of said casing to remove from said casing the powdered material floating in said gas.

20 25 30 35

7. The combination with an impact pulverizer comprising a pair of aligned nozzles spaced apart and arranged to discharge toward each other streams of small pieces of solid matter impelled by superheated steam at high temperature, pressure and velocity whereby said pieces are pulverized by their impact against each other, of a casing forming an impact chamber and enclosing said nozzles, a bottom wall of said casing being inclined sharply downwardly and positioned directly under both of said nozzles and terminating in an opening offset laterally from the vertical passing through the axes of said jets whereby any material from said nozzles not reduced to powder and striking said bottom wall will slide downwardly over the surface

40 45 50 55 60 65 70 75

In witness whereof, I have hereunto set my hand this 30th day of January, 1925.

ALFRED B. WILLOUGHBY.
